NAIL CHUCK

Floyd G. Paxton and Albert I. Obermiller,
Riverside, Calif.

Application October 22, 1947, Serial No. 781,308

3 Claims. (Cl. 1—5)

1

Our invention relates to nailing machines and more particularly to an improved nailing head for use on such machines. The type of machine to which the present invention relates is commonly used for nailing wooden boxes and for nailing lids on boxes. These machines include a frame having a nailing table for supporting the work to be nailed. A group of nailing heads is supported on the frame above the table for driving nails in the work, the heads being adjustable to obtain the desired nail pattern for different sizes and types of boxes.

A nail-feeding mechanism, common in the art, is provided for stripping the nails and automatically feeding a single nail through a tube to each nailing head at each cycle of operation. The machine brings the work and the nailing heads together and the nails are driven from the nailing heads into the work by nail drivers which are slidable in the heads, the nail drivers being power driven by the machine.

During operation of nailing machines, the nailing heads occasionally jam when bent, malformed, or oversize nails are fed to the nailing head. It is not uncommon to find a number of nails in a single keg which are deformed and cause the nailing head to jam. The conventional heads in present use are designed to yield in the event of a jam to prevent serious damage or breakage of the head. Such heads usually comprise a body formed of two halves. The halves are held in alignment by a pair of studs which are threaded into and extend from one of the halves, the other half of the nailing head body being slidable on the studs. The two halves are yieldably held together by a pair of compression springs, one spring on each stud, the springs being compressed by nuts threaded on the studs.

When the nailing heads of a machine become jammed, the head must be taken apart to clear the trouble. To disassemble the conventional head, the nuts which compress the springs are removed, many turns of the nuts being required as the studs are of sufficient length to enable compressing and decompressing the springs. After removal of the nuts, the springs are removed and finally the free half of the head. When the jam is cleared, the head is assembled by reversing the steps above described.

The time required to clear the conventional type of nailing head is highly objectionable, particularly when the nailing machine is being used on lidding operations where the boxes are carried from the packing stations to the lidding machine on a conveyor in a continuous line. Some

2

boxes are lidded at an average rate of 1200 boxes per hour and maximum speeds of as high as 1800 boxes per hour are obtainable. A delay at the lidding machine beyond a certain limit results in congestion of packed boxes along the conveyor which forces the packers to remain idle until the lidding machine is repaired and the congestion cleared.

It is, accordingly, an object of the present invention to provide an improved nailing head which may be disassembled and reassembled in but a fraction of the time required to disassemble and reassemble the conventional head.

A further object of our invention is to provide a nailing head which can be taken apart and reassembled without the use of wrenches or other tools.

Another object hereof is the provision of a nailing head spring assembly in which the springs are retained under compression when the springs are removed from the nailing head thereby relieving the operator of the work required to decompress the springs when disassembling the nailing head and to compress the springs when assembling the head.

Another object of our invention is the provision of a self-locking spring retainer which holds the springs of a nailing head under constant pressure without working loose during vibration and shock of the machine during nailing operations.

Still another object hereof is the provision of a spring assembly in which the springs are permanently compressed to the proper degree thereby making it impossible for an inexperienced or careless operator to over or under compress the spring when assembling a nailing head.

A further object of our invention is to provide a nailing head of reduced thickness thereby permitting the vertical axes of adjacent nailing heads to be brought close together to enable the driving of nails on relatively close center to center distances when desired.

Other advantages and objects will become apparent in the following description in view of the drawings in which:

Fig. 1 is a front elevational view of a preferred form of nailing head of our invention.

Fig. 2 is a side view of the nailing head shown in Fig. 1.

Fig. 3 is a vertical sectional view taken on line 3—3 of Fig. 2.

Fig. 4 is a horizontal sectional view taken on line 4—4 of Fig. 1.

Fig. 5 is a front view similar to Fig. 1 but show-

ing the first step in disassembly of the nailing head.

Fig. 6 is a perspective view showing the main parts of the nailing head as they appear when disassembled.

Referring specifically to the drawings, a preferred form of nailing head of our invention is indicated generally throughout the several views at 10. The nailing head 10 includes a body 11 comprised of two sections, a stationary section 12 and a floating section 13.

The stationary section 12 is shaped at its upper end to provide shoulders 14, as seen in Fig. 1, which serve to position the nailing head 10 in relation to a pair of bars 15 to which the head 10 is secured by a cap screw 16. The bars extend horizontally, as seen in Figs. 2 and 6, and are secured to the frame of the nailing machine (not shown) in a well-known manner. In practice, a number of the nailing heads 10 are secured to the bars 15 for driving a row of nails into the work to be nailed. The heads are readily adjustable along the bars 15 to obtain the desired nail spacing.

Secured to opposite sides of the stationary section 12 by means of rivets 20 is a pair of guide bars 21, the latter being set in channels 22 milled on opposite sides of the section 12. As seen in Fig. 2, the outer surfaces of the guide bars 21 are flush with the outer surfaces of the stationary section 12. The free ends of the guide bars 21 are formed to provide hooks 23 having semi-circular recesses 24 and openings 25. As seen in Fig. 2, the guide bars 21 are relatively thin for the purpose of reducing the overall thickness of the nailing head 10 to a minimum. In actual practice, the overall thickness of the head 10 does not exceed five-eighths of an inch although the head is designed to drive nails as large as eightpenny. Two or more heads can therefore be positioned to drive nails on as little as five-eighths of an inch center to center spacing.

The floating section 13 has channels 28 milled on opposite sides thereof as best seen in Fig. 6. The channels 28 slidably receive the guide bars 21 which properly orient the sections 12 and 13 while permitting horizontal movement of the floating section 13 relative to the stationary section 12.

Formed longitudinally along the adjacent inside faces of the body sections 12 and 13 are nail-driver channels 29 and 30 respectively as shown in Figs. 3 and 4. When the sections 12 and 13 are closed in normal nail-driving relation, the channels 29 and 30 form a square passage for slidably receiving a nail driver 31. The nail driver 31 is a square bar of hardened steel, attached at its upper end to a vertically movable nail-driving bar (not shown), a well-known element in the nailing machine art.

Both of the nailing head sections 12 and 13 have cavities 35 and 36, respectively, at the lower portions thereof as seen in Fig. 3. The cavities 35 and 36 are shaped to receive the nail chuck 37 comprised of a pair of complementary steel chuck springs 38 mounted on the sections 12 and 13 by means of screws 39. The springs 38 are shaped to receive the point of a nail 40, as seen in Fig. 3, and also serve to guide the nail 40 as the latter is driven from the head 10 into the work by the nail driver 31 in a well-known manner. Formed in the floating section 13, as shown in Fig. 3, is a hole 44 for receiving a nail-feeding tube 45, the latter being secured in the section 13 by a set screw 46.

Slidable on the guide bars 21 is a spring pres-

sure unit 50 which includes a frame member 51, opposite edges of the latter being shaped to slidably receive the guide bars 21 as indicated at 52. Opposite ends of the frame member 51 have holes 53 for receiving rivets 54, the latter being slideable in the holes 53 and having heads 55 and 56 at opposite ends thereof. Mounted on each of the rivets is a compression spring 57 confined longitudinally between the rivet heads 55 and ends of the frame member 51. The pressure unit 50 is assembled by heading the rivets 54 with the springs 57 under compression. After the pressure unit 50 is assembled, the springs 57 are permanently compressed by an amount suitable for proper operation of the nailing head 10.

The nailing head 10 is locked up after assembly by a cam 60 shown best in Fig. 6. The cam 60 is comprised of a cylindrical head 61 having trunnions 62 on opposite ends thereof. The trunnions 62 are on a common axis which is eccentric in relation to the axis of the head 61. Extending from the head 61 is a handle 63 provided for manual operation of the cam 60 and also for limiting rotation of the head 61. The cam 60 is locked in position by placing the trunnions 62 in the semi-circular recesses 24 of the guide bars 21 with the cam 60 in the position in which it is shown in Fig. 5. It will be noted by the dotted lines in Fig. 5 that while in this position, the head 61 of the cam 60 does not contact the frame member 51 of the spring pressure unit 50. As the handle 63 is forced downward to the position shown in Fig. 1, the head 61 contacts the frame 51 and presses the springs 57 against the floating section 13 thereby forcing the section 13 against the stationary section 12. When the handle 63 stops against the head 56 of the lower rivet 54, the cam is locked against accidental displacement because the axis of the cylindrical head 61 is well above the axis of the trunnions 62 as seen in Fig. 1.

Operation

The normal operating positions of the various parts of the nailing head 10 are as shown in Figs. 1 to 4, Fig. 3 showing the proper position of the nail 40 prior to driving. If the head 10 becomes jammed as a result of a deformed nail, or as a result of two nails instead of one being fed to the head, the floating section 13 is forced away from the stationary section 12 against the pressure of the springs 57. To clear the jam, it is necessary to disassemble the head and remove the deformed nail. The first step in disassembling the nailing head 10 is removal of the cam 60 by lifting the handle 63 to the position shown in Fig. 5 thereby relieving the cam 60 of the pressure of the springs 57 and permitting removal of the cam 60. The pressure unit 50 and floating section 13 of the nailing head 10 are withdrawn from the guide bars 21 as shown in Fig. 6. After the head is cleared, reassembly is accomplished in but a few seconds by reversing the steps followed in disassembly.

It is clear that disassembly and assembly of the nailing head 10 can be accomplished in a minimum of time, without the use of tools, and that upon assembly, the proper pressure of the springs 57 is automatically accomplished without depending upon the degree of skill and care exercised by the operator.

Although we have limited the present disclosure to but one form of our invention, it is understood that modifications and changes may be made in the structure without departing from the scope of the following claims.

We claim as our invention:

1. In a nailing head, the combination of: a body divided longitudinally to form two sections, one of said sections being movable toward and away from the other, guide means for maintaining said sections in alignment relative to each other, a spring pressure unit for urging said movable section toward the other, and a cam engageable with said guide means and said spring pressure unit, said cam being manually operable for urging said spring pressure unit into operative position and locking said unit in said position.

2. In a nailing head, the combination of: a body divided longitudinally to form a stationary section and a floating section, a nail driver slideable longitudinally between said sections for driving a nail from said head, a pair of guide bars extending from said stationary section, said floating section being slideable on said guide bars toward and away from said stationary section, a pressure unit comprising a frame slideable on said guide bars, a spring secured to said frame, means for retaining said spring in partially compressed condition, and a manually operable cam for removable engagement with the free ends of said guide bars, a lever for manual rotation of said cam, said cam urging said pressure unit against said floating section in response to rotation of said cam.

3. In a nailing head, the combination of: a body divided longitudinally to form a stationary

section and a floating section, a nail driver slideable longitudinally between said sections for driving a nail from said head, a pair of guide bars extending from said stationary section, said floating section being slideable on said guide bars toward and away from said stationary section, said guide bars having hooks formed on extremities thereof, a pressure unit comprising a frame slideable on said guide bars, a spring secured to said frame, means for retaining said spring in partially compressed condition, a rotary cam having aligned trunnions on opposite sides thereof, said trunnions being removably engageable with the hooks of said guide bars, means for rotating said cam against the frame of said pressure unit to urge said pressure unit against said floating section to yieldably retain said floating section against said stationary section, and a stop halting rotation of said cam after the high-point of said cam passes the line of contact between said cam and said frame.
